TERRENCE COLLINS AND ASHER CASTIEL, OF ST. LOUIS, MISSOURI.

Letters Patent No. 88,452, dated March 30, 1869.

IMPROVEMENT IN LATHE.

The Schedule referred to in these Letters Patent and making part of the same.

To all whom it may concern:

Be it known that we, TERRENCE COLLINS and ASHER CASTIEL, of St. Louis, in the county of St. Louis, and State of Missouri, have made certain new and useful Improvements in Machines for Turning Irregular Forms, and Cutting Roped Mouldings; and we do hereby declare that the following is a full and clear description thereof, reference being had to the accompanying drawings, and to the letters of reference marked thereon.

The object of this invention is to turn irregular forms, and especially such as have a part circular and part rectangular section, and to cut thereon a moulding, or bead on such portion of said section as may be desired; and the application thereof is especially to form roped moulding-strips, with a rectangular corner, to fit (without the interposition of any additional pieces) the corners of window or door-frames, and similar places.

This invention consists in the use of a series of cutters supported upon a table, so arranged, that when desired, they may be raised entirely off from the material being operated upon, or lowered to cut to any desired depth.

And it consists, furthermore, in the arrangement and combination of certain devices, by which such object is attained, and which are hereinafter fully described.

To enable others to make and use our improvement, we will proceed to describe its construction and operation.

Figure 1 is a front elevation.

Figure 2 is a top plan.

Figure 3 is a transverse sectional elevation.

Figures 4 and 5, an elevation and plan, respectively, of the moulding-cutters.

The operating-devices of our machine are supported upon a frame, A, made of the usual materials, and of the general form indicated in the drawings.

At the rear end of said frame, supported in proper journal-bearings, is the driving-shaft B, having pulley b, and which transmits power and motion to counter-shaft c, having pulley c', by belt b'.

On shaft C are arranged pulleys D G, having belts d g, which transmit motion to the arbor E, carrying the cutter F, for cutting the circular part of the material being operated upon, and also the arbor H, carrying the cutter I, for cutting roped mouldings, there being additional pulleys and belts for communicating motion to arbors H¹ H², having additional cutters, I¹ I², arranged similarly.

Arbor E, having cutter F, is placed horizontally in bearings e', upon the table K; said cutter F being of any of the ordinary forms for cutting stuff to a circular section, employed in wood-working machinery.

The arbors H¹ H², having cutters I¹ I², are supported vertically by bearings h' upon the table K, aforesaid.

The material to be operated upon is held in supports L, directly under the cutters aforesaid, said supports being secured to the frame A, and arranged with bushing, or holders L¹, having central openings l, which correspond to the sectional outline of the material. Thus in the cornered roped mouldings, especially intended to

be formed in one application of the machine, said holders will have an opening, l, to correspond to the area of the stuff, as shown at x, in fig. 3, being circular, excepting in one quadrant, where the square corner remains.

The holders L¹ have spur-gearing L² in their outer surfaces, which connect with gear-wheels M, of shaft m, said gearing being again in connection with the gear-wheel N, of the shaft n.

Shaft n has, at its outer end, a bevel-wheel n', connecting with the bevel-gear wheel O', upon the shaft O.

Shaft O has pulley O², which is connected by a belt with power-shaft B, and thus all parts are put in motion.

Thus, by the transmission of power and motion aforesaid, and by the especial construction of holders L¹ the stuff is revolved under the cutters F, and I I¹ I², and cut into the desired forms.

In order to feed the material being operated upon, forward to the operation of the cutters, a standard, P, resting upon rack P', is arranged. Said rack is operated upon by the spur-wheel o upon shaft O, above referred to. The material being held in the standard P, and passing through the holders L¹, aforesaid, will, by the operation of said rack P', be fed forward, as required.

In order that the action of the several cutters may be withheld, or gradually withdrawn, and the material being operated upon, assume the irregular form required, the table K, on which the cutter-arbors E and H are supported, is supported upon central lifter Q, said lifter being operated by rod q, actuated by cam-rod R and cam r, said cam being upon the shaft n, above referred to.

Cam-rod R is provided with double prongs, which engage the cam r, which said cam r must exactly correspond in form to the sectional figure, or outline of the article to be produced, as shown at x, fig. 3.

The moulding-cutters I I¹ I², are of a pear-shape, with cutting-edges i, as shown in figs. 4 and 5, said form being adapted to cut the usual roped mouldings. By reversing the cutting-edges of the cutters I I¹ I², and circular cutter F, and also the rotary motion of the arbors E, and H¹ H², a left moulding will be produced.

Thus, by the employment of a second set of cutters alone, without the use of additional appliances, both right and left mouldings are produced.

We do not claim, as new, any of the devices singly, for they are old and in use; but,

What we do claim, and desire to secure by Letters Patent is—

The cutters F I I¹ I², supports L, holders L¹, standard P, rack P'; and operated as described, in combination with the table K, cam r, and its connections with table K, and the devices for operating the same, in the manner and for the purpose substantially as described.

TERRENCE COLLINS.
ASHER CASTIEL.
